Primary Examiner — Cynthia Ramirez(74) *Attorney, Agent, or Firm* — Kolisch Hartwell, P.C.(57) **CLAIM**

The ornamental design for a rail pallet, as shown.

DESCRIPTION

FIG. 1 is a perspective view of a rail pallet showing our new design;
FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The shading lines shown in the drawings represent the approximate three-dimensional contour of the design, and are not intended to indicate surface decoration.

The rail pallet is shown with a symbolic break in its length. The appearance of any portion of the article between the break lines forms no part of the claimed design.
